[57] **CLAIM**

The ornamental design for a hypodermic syringe destruction and disposal device, substantially as shown and described.

DESCRIPTION

FIG. 1 is a perspective view of the device of my new design as seen from a point above and diagonally outward from the right front corner of the device, and illustrating the top, front and right sides of the device. A perspective view taken from a like reference point with respect to the right rear corner of the device would be the mirror image of the view shown in FIG. 1 and would show the top, left side and rear of the device hypodermic syringe destruction and disposal. A perspective view taken from a like reference point with respect to the left rear corner of the device would display the left side as being identical to the right side and the rear side as being identical to the front side.

FIG. 2 is a bottom view thereof on a reduced scale.

FIG. 3 is a sectional view thereof taken along line 3—3 of FIG. 2.

FIG. 4 is a front elevational view thereof;

FIG. 5 is a side elevational view thereof.

FIG. 5

FIG. 4
